UNITED STATES PATENT OFFICE.

WILLIAM S. McCLEUNG, OF HEREFORD, TEXAS.

CONDIMENT-HOLDER.

1,184,549.

Specification of Letters Patent. Patented May 23, 1916.

Application filed April 4, 1914. Serial No. 829,534.

To all whom it may concern:

Be it known that I, WILLIAM S. McCLEUNG, a citizen of the United States, residing at Hereford, in the county of Deaf Smith and 5 State of Texas, have invented new and useful Improvements in Condiment-Holders, of which the following is a specification.

The invention relates to condiment holders, and has for an object to provide a 10 simple device that can be easily and cheaply manufactured and which is preferably adapted for use on a table to dispense salt and pepper, the two mentioned condiments being contained in a single receptacle or 15 vessel, whereby they can be independently sifted therefrom by the user.

The invention contemplates, among other features, the provision of a condiment holder which consists of few parts that can 20 be readily formed of stamped metal so that the condiment holder can be cheaply manufactured, although the same may also be made up in a highly finished product.

In the further disclosure of the invention 25 reference is to be had to the accompanying drawings, constituting a part of this specification, in which similar characters of reference denote corresponding parts in all the views, and in which:

30 Figure 1 is a perspective view of the condiment holder; Fig. 2 is a vertical sectional view taken through the condiment holder; and Fig. 3 is a vertical sectional view taken through the condiment holder on a line perpendicular to the vertical section shown in Fig. 2.

Referring more particularly to the views, I provide a receptacle 10 in which is arranged a partition 11 forming a plurality 35 of compartments 12, 13 in the receptacle 10, with one of the said compartments adapted to hold pepper and the other salt.

A top 14 is provided for the receptacle 10 and consists, more particularly, of a disk 15 45 having two sets of perforations 16 and 17 therein, with the perforations 16 adapted to communicate with the compartment 12 and the perforations 17 adapted to communicate with the compartment 13. The disk 15 carries an annular flange 18 forming a part of the top and which is adapted to encircle the receptacle 10 when the top is fitted thereon. Formed in the disk 15 is a diametrically extending groove 19 and a flap 20 of a semi-circular construction preferably has its straight edge bent to form a hinge 21,

through which passes a wire 22 having its ends soldered or otherwise suitably secured to the annular flange 18, said hinge 21 lying in the groove 19 of the disk and loosely arranged therein, and supported by the wire so that the flap can be swung from one side to the other of the groove to cover either set of perforations 16 and 17 in the disk. The flap 20 is provided with a bead 23 struck from the flap, with the said bead adapted for engagement with spring-like catches 24 secured to or formed with the annular flange 18 of the top 14, the said spring-like catches being diametrically opposed so that when 70 the flap is in position to close the perforations to the pepper compartment it can be engaged with one of the said catches, whereas when it is in position to close the perforations to the salt compartment the said flap 75 can be engaged with the other spring-like catch.

In order to hold the top 14 against accidental removal from the receptacle 10 the annular flange 18 of the top has secured thereto or formed therewith a spring-like locking member 25 adapted to project into a notch 26 formed in the receptacle 10 so that a portion of the said locking member engaging the part of the wall of the notch 85 will hold the top against removal from the receptacle until the locking member is first removed from the notch in the receptacle.

It will be noted that the opposed faces of the flap 20 are marked with the words "Salt" 90 and "Pepper" and when the flap is in position to uncover the perforations to the salt compartment the word "Salt" will appear plainly on the exposed face of the flap, whereas when the flap is in position to uncover the perforations to the pepper compartment the word "Pepper" will appear plainly on the exposed face of the flap, it being of course understood that when the perforations to the salt compartment are 100 uncovered the perforations to the pepper compartment will be covered by the flap and vice versa. It will be apparent that the device described is of a simple construction, and consists of few parts which can be very 105 cheaply manufactured.

In order to position the top properly upon the receptacle 10 the upper edge of the partition 11 is provided with a groove 27 into which is adapted to fit a rib 28 struck from the under side of the top 14 and which is formed when the groove 19 is struck into the

upper face of the top. With this construction the top, when placed upon the receptacle, will be required to have the rib 28 extend into the groove 19, thus causing the perforations for the receptacle compartments to properly register therewith.

Having thus described my invention, I claim:

A condiment holder consisting of a cylindrical container, a vertical partition extending in a median line in said container, a substantially U-shaped portion formed transversely at the upper edge of said partition and spaced below the outer edge of the container, a cap fitting the upper edge of said container snugly, said cap being formed throughout its surface with a plurality of ports, said cap being formed at a median line with an outstruck double portion ar-

ranged at right angles thereto and extending transversely thereof, said double portion seating in said U-shaped portion, said cap being formed in a plane with said double portion with a recess, a sector-shaped lid adapted to cover opposite parts of said cap, a bead formed upon said lid adapted to seat in said recess, a wire passed through said bead and having right angular terminals straddling said cap and secured thereto, and means for frictionally holding said cap on said container, said lid being held in closed position.

In testimony whereof I affix my signature in presence of two witnesses.

WILLIAM S. McCLUNG.
